INSPECTION DEVICE

Kenneth J. Yost, Westport, Conn., assignor to
Remington Arms Company, Inc., Bridgeport,
Conn., a corporation of Delaware

Application May 2, 1942, Serial No. 441,562

4 Claims. (Cl. 209—82)

The present invention relates to an improved inspection device, particularly for use in connection with the feed of a row of articles into a machine for operating upon them, as for instance a draw-press, and wherein the articles must not only be arranged in proper upright position, but must be of the correct size for the particular machine, and un-deformed in shape. It is an object of the invention to provide such an inspection device which will pass articles along the feed line which are in proper position of correct size, and un-deformed, but will stop the feed of any articles failing to meet these requirements.

While the invention is capable of use with various types of articles and feed lines, as will be apparent from the following description, the embodiment of the invention illustrated herein by way of example is particularly concerned with the inspection and feed-stopping of the metal cup pieces from which are drawn cartridge cases. These pieces are in the form of a shallow, heavy-walled cylindrical cup, usually received by the cartridge manufacturer from metal manufacturers, and in the cartridge manufacturing procedure are individually fed to the first draw-press by a friction-dial which normally carries the cups forward into relation to the feed slide of the draw-press, but slides under them if the movement of the cups is obstructed. The metal suppliers sometimes inadvertently mix cups of different sizes, and cups are sometimes deformed, so that the wall which is normally cylindrical may be oval, or may be indented or otherwise deformed from its normal shape, and if these wrong-sized or deformed cups reach the draw-press the drawing punch cannot enter them, and considerable damage to the tools and delay is apt to result. Such damage and delay will also result if a foreign object is nested in the cup or if a cup reaches the draw-press in an inverted position, that is with its closed end up instead of in its normal open-end up position. The present device is intended to detect and stop the feeding of any cups which are not of the correct size and formation, which are not in proper open-end up position, or in which foreign objects are nested, whereupon the machine operator may remove such cups from the feed line.

Heretofore it has been the practice to employ a freely rotating star-wheel device in the feed line having relatively thin teeth designed to engage the open end of the cups and pass them in the feed line, but which stops the feed of inverted cups, as well as cups in which are nested foreign objects. This previously known star-

wheel does not detect cups of the wrong size or bent-mouth cups.

It is proposed in the present invention to provide an inspection device in the form of a loosely rotating star-wheel having instead of the thin teeth of the previously known star-wheel a series of buttons, each constituting a cylindrical gauge adapted to be automatically fitted into the circular open end of a perfect cup but which will not enter one which is undersized, deformed, inverted or contains foreign objects.

A further object is to provide a cup inspection star-wheel provided with buttons, each having a projecting spherical nose or crown portion for entering the cup cavity and determining that it is of proper depth and free from foreign objects, and a connecting conical surface between such spherical nose and the cylindrical gauge surface of the button which will clear the edges of the cups as they are fed and passed along the feed line with the cups either single or in successive contacting relation with each other. Consequently, the buttons are so shaped that one button will disengage from one cup as the following button enters a successive cup with two cup wall thicknesses moving in the space between the buttons. This is the condition when a line of perfect cups is being fed without interruption. In case of one of the cups being stopped because of being undersized, deformed or inverted, this cup may be removed while the preceding cup in the line has been passed and is out of engagement with the star-wheel buttons which may then be in an indeterminate position. In this case, the next cup to be fed into relation with the star-wheel is the first cup in the feed line and engages at its outer wall surface with the particular button that may be positioned in its path in the feed line and causes the star-wheel to rotate. In this case there is only a single cup wall thickness between the first engaged button and the following button which is to enter the cavity of the cup, and it is an object of the invention to provide such spacing of the buttons and such clearance in the button surfaces that the button following the button first engaged and propelled by the cup will freely enter the cup cavity and will thereupon be propelled in its rotation by the forward feeding of the cup, which itself is propelled forwardly by the following cups in the feed line. Accordingly, the star-wheel of the invention is such that a cup is capable of picking up and rotating the star-wheel from any position of the star-wheel without blocking movement of the wheel by the next succeeding cup.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a plan view of the cup feed part of a draw-press, provided with an inspection device according to the illustrated exemplary embodiment of the invention.

Fig. 2 is a vertical sectional view, taken along the line 2—2 of Fig. 1.

Fig. 3 is a plan view of the inspection device, and showing a portion of the cup feeding dial 13 and feed line guide-way in relation thereto.

Fig. 4 is a front elevation showing one of the cup members partially in vertical section in relation thereto.

Fig. 5 is a side elevation and showing a row of cup members in vertical section, one of the cup members being in vertical aligned relation with the axis of the star-wheel.

Fig. 6 is a side elevation, showing the row of cup members advanced and the star-wheel rotated from the position as shown in Fig. 5 and with the line of contact between two cup members vertically aligned with the axis of the star-wheel.

Fig. 7 is a side elevation showing an inverted cup member in its position as stopped by the star-wheel.

Fig. 8 is a side elevation showing the relation of the first cup member of a row or a single cup member at the point when it engages the star-wheel to be passed under it and showing in dot-and-dash lines a further advanced position where a button member is engaging its open end.

Fig. 9 is a side elevation showing the inspection device of the invention as applied to an inclined gravity feed article guiding chute.

Fig. 10 is a side elevation showing a modification including a counting device.

Similar reference characters indicate corresponding parts throughout the several figures of the drawings.

Referring to the drawings, the draw-press illustrated by way of example in Figs. 1 to 8, is provided with a horizontal table 10 having a circular opening 11 therein in which is engaged the cup feeding dial 12 mounted upon a drive shaft 13, the upper surface of the dial being flush with the upper surface of the table. Adjacent the periphery of the table there is provided a slide-way 14 having a reciprocating cup feeding slide 15 engaged therein and having its upper surface flush with the upper surface of the table 10 and the dial 12, this slide being provided with a cup receiving pocket 16, which in one position of movement of the slide is in vertical line with the draw-punch 17 and draw-die 18, and in the other position of movement is in line with the cup feeding guide-way.

The cup feeding guide-way consists of a pair of parallel side-wall members 19 and 20 extending for a short distance over the table 10 from the slide 15 to the surface of the dial, and extending for a substantial distance over the dial surface in concentric relation thereto near its periphery, so that rotation of the dial causes the row of cup members within the guide-way to be fed forwardly toward the slide 15 by frictional contact therewith, the dial sliding beneath the cup members when there is any obstruction in their movement. The wall members 19 and 20

are suitably supported above the dial by means of bracket members 21 secured to the table 10. At the forward end of the guide-way formed by the parallel walls 19 and 20 these walls diverge to provide a converging entrance for the cup members, the wall 19 being extended in concentric relation to the outer periphery of the dial to the opposite side thereof, as at 19^a, and the wall 20 being curved rearwardly and extended transversely across the face of the dial to the opposite side, as at 20^a, to provide a relatively large area upon the dial surface, enclosed by the wall portions 19^a and 20^a, in which the cup members may be placed in quantity either manually or by suitable mechanical means, the movement of the dial forcing the cup members toward and into the guide-way entrance.

At the forward end of the parallel wall guide-way, adjacent the converging entrance point where the cup members form into a single row in the guide-way, there is provided the inspection device according to the invention. This device comprises a mounting bracket 22 provided at the lower portion of its inner side with an arcuate recess 23 conforming to the curvature of the guide-way wall member 19 and engaged upon the outer side of the wall 19 and secured thereto by screws 24. The bracket extends vertically above the wall 19, and is provided with a vertical shaft mounting slot 25, the axis of which is in radial line with the supporting shaft 26 for the rotary star-wheel, this shaft having at its outer end a retaining head 27 and at its inner end a reduced diameter threaded attaching stud 28, engaged through the slot 25 and secured therein by a nut 29. The slot 25 permits limited vertical adjustment of the shaft and star-wheel.

The star-wheel comprises a hub 30 mounted for free rotation upon the shaft 26, and preferably provided with an oil hole 31 for convenient lubrication of the bearing. Within the cylindrical periphery of the hub there are provided a series of cylindrical radially disposed pockets 32 in which are engaged the cylindrical shank portions 33 of the button members, secured therein by cross pins 34 rivet-headed over at their ends.

Various profiles and combinations of curves may be employed for the button members as desired. Merely, by way of example, one form of a button member may include a cylindrical cup gauging portion 35 adjacent the hub, a projected spherical nose portion 36, having a radius somewhat less than the radius of the diameter of the cylindrical gauge portion 35, and a connecting cone portion 37 between the outer end of the cylindrical gauge portion 35 and the spherical nose portion 36, its surface being tangential to the surface of the nose portion. It should be pointed out that the diameter of the cylindrical gauge portion 35, the radius and projection of the nose portion 36, and the spacing between the several button members of the star-wheel are calculated with relation to the shape and dimensions of the particular type of cup member being inspected, having in view the diameter of the cup member, its wall thickness, its height, and the depth of its open-end pocket. In practice, the diameter of the gauge portion 35 is slightly less than the diameter of the pocket of the cup member, so that it will engage within the cylindrical pocket with just sufficient clearance to permit the button to be rotated into and out of engagement with the cup member as it is moved by the dial along the guide-way. Any slight varia-

tion in the normal cylindrical shape of the pocket will not allow the cylindrical gauge portion 35 of the button member to engage therein. The spacing of the button members in the star-wheel is determined by the wall thickness of the cup members so that two wall thicknesses of a pair of adjacent cup members will pass between two of the button members as the star-wheel is rotated and as shown clearly in Fig. 6, while the projection and radius of the nose and the clearance afforded by the conical connecting portion are determined by the relation of a single cup member, or the first one of a row, which first engages at its leading edge with one of the star-wheel buttons disposed in an indeterminate position in its path, the projection and radius being such that the following button will freely swing into the open-end pocket of this single or first cup member. This is shown clearly in Fig. 8, wherein the full lines show the single cup member engaged at its leading edge with one button of the star-wheel, and the dot-and-dash lines show the same cup member in a further propelled position with the following button engaging its open-end pocket, this following button at this point being propelled by the continued forward movement of the cup member to rotate the star-wheel.

In Fig. 7 I have shown an inverted cup member A¹ disposed in the feed line in its relation to the star-wheel, one of the buttons being stopped in engagement with the up-turned button surface of the cup member and stopping rotation of the star-wheel. This prevents movement of the next cup member A in front of the inverted cup member until the operator of the machine removes the inverted cup member from the line, whereupon the star-wheel is free to rotate. In the case of a deformed cup member, or a small size cup member, the button will be prevented from entering the open-end as the cylindrical gauge portion will not fit it, and rotation of the star-wheel will be stopped until the deformed or undersized cup is removed. In Fig. 1, I have illustrated among the cup members on the dial a perfect open-end up cup member A, an inverted cup member A¹, an undersized cup member A², and a deformed cup member A³.

A forked stripper 40 with forked ends 41 straddling the buttons is shown in Figs. 3 and 5 which may be used if desired to insure removal of cups from the buttons. The other end of the stripper may be fastened in any suitable manner to the frame of the machine.

A further modification is shown in Fig. 10 wherein a conventional counting mechanism is attached to the star-wheel so as to count the number of cups passing. The revolution counter 43, of any well known type, is fastened to bracket 44, which in turn is held stationary relative to the bracket 22 by nut 29. A hole 45 may be drilled through bolt 46 and a pin 47 passed therethrough. The end 48 of pin 47 may be fastened to plate 49 so as to turn with the hub 30. Plate 49 is fastened to hub 30 by means of screws 52. The opposite end 51 of the pin 47 may be fastened in a suitable manner to the operating shaft of the counter. The head 50 of bolt 46 may be countersunk as indicated. It is to be understood that the mounting means shown is merely exemplary. The counter thus will be operated by the hub 30 through plate 49 and pin 47.

In Fig. 9, I have illustrated an alternative form of feed line in which the star-wheel according to the invention may be incorporated. This consists of an inclined chute member 38 along which

the cup members are propelled by gravity to the draw-press or other machine, the star-wheel supporting bracket being mounted upon one side wall of the chute and the star-wheel being disposed and operated in the feed line in substantially the same manner as in the dial-propelled feed line.

The form of the invention illustrated in the drawing and described herein is typical and illustrative only, and it is evident that the invention is capable of embodiments in other forms, all falling within the scope of the appended claims, which are to be broadly construed.

What is claimed is:

1. In an inspection device for a feed line of cylindrical-walled open-end-up cup members propelled in a guide-way in single file arrangement, a star-wheel rotatably arranged in said guide-way comprising a hub and a series of radial equally spaced button members carried by said hub adapted as said feed line is propelled to successively engage the open upper ends of successive cup members in said feed line through rotation of said star-wheel, each of said button members comprising a cylindrical gauge portion adjacent the hub normal to the radial button axis adapted to fit the cylindrical open end of said cup members with slight clearance, a projecting spherical nose portion having its radius less than the radius of said cylindrical gauge portion, and a clearance portion between said nose portion and said cylindrical gauge portion.

2. In an inspection device for a feed line of cylindrical-walled open-end-up cup members propelled in a guide-way in single file arrangement, a star-wheel rotatably arranged in said guide-way comprising a hub and a series of radial equally spaced button members carried by said hub adapted as said feed line is propelled to successively engage the open upper ends of successive cup members in said feed line through rotation of said star-wheel, each of said button members comprising a cylindrical gauge portion adjacent the hub normal to the radial button axis adapted to fit the cylindrical open end of said cup members with slight clearance, a projecting spherical nose portion having its radius less than the radius of said cylindrical gauge portion, and a conical clearance portion tangential to said spherical nose portion and extending to the outer edge of said cylindrical gauge portion.

3. In an inspection device for a feed line of cylindrical-walled open-end-up cup members propelled in a guide-way in single file arrangement, a star-wheel rotatably arranged in said guide-way comprising a hub and a series of radial equally spaced button members carried by said hub adapted as said feed line is propelled to successively engage the open upper ends of successive cup members in said feed line through rotation of said star-wheel, each of said button members comprising a cylindrical gauge portion adjacent the hub normal to the radial button axis adapted to fit the cylindrical open end of said cup members with slight clearance as the radial button axis is in line with the central axis of the cup member, a projecting spherical nose portion having its radius less than the radius of said cylindrical gauge portion, and a conical clearance portion tangential to said spherical nose portion and extending to the outer edge of said cylindrical gauge portion, the radial spacing of said button members being such with respect to the wall diameter and height of said cup members that two wall thicknesses of a pair of ad-

adjacent contacting cup members may pass between the cylindrical gauge surfaces of adjacent button members.

4. In an inspection device for a feed line of cylindrical-walled open-end-up cup members propelled in a guide-way in single file arrangement, a star-wheel rotatably arranged in said guide-way comprising a hub and a series of radial equally spaced button members carried by said hub adapted as said feed line is propelled to successively engage the open upper ends of successive cup members in said feed line through rotation of said star-wheel, each of said button members comprising a cylindrical gauge portion adjacent the hub normal to the radial button axis adapted to fit the cylindrical open end of said cup members with slight clearance as the radial button axis is in line with the central axis of the cup member, a projecting spherical nose portion having its radius less than the radius of

said cylindrical gauge portion, and a conical clearance portion tangential to said spherical nose portion and extending to the outer edge of said cylindrical gauge portion, the radial spacing of said button members being such with respect to the wall diameter and height of said cup members that two wall thicknesses of a pair of successive contacting cup members may pass between the cylindrical gauge surfaces of adjacent button members, and the radius and projection of said nose portions being such with respect to the radial spacing of said button members and the wall diameter and height of said cup members that a single cup member engaged at its outer wall surface with one of said button members will through rotation of said star-wheel be freely engaged at its open end by the next following button member of said star-wheel.
